UNITED STATES PATENT OFFICE.

GUSTAVE E. BLISS, OF NEWARK, NEW JERSEY, AND FRED SMART, OF NEW YORK, N. Y.

DESIGN FOR A MEMORANDUM-PAPER HOLDER.

56,581.

Specification for Design.

Patented Nov. 16, 1920.

Application filed April 12, 1920. Serial No. 373,405. Term of patent 7 years.

To all whom it may concern:

Be it known that we, GUSTAVE E. BLISS, a citizen of the United States, and a resident of Newark, county of Essex, and State of New Jersey, and FRED SMART, a subject of the King of Great Britain, and a resident of New York city, county and State of New York, have invented a new, original, and ornamental Design for a Memorandum-Paper Holder, of which the following is a specification, reference being had to the accompanying drawing, forming part hereof.

The drawing is a perspective view of the holder showing our new design.

What we claim is:—

The ornamental design for a memorandum paper holder, substantially as shown.

GUSTAVE E. BLISS.
FRED SMART.
